ELECTRON DISCHARGE APPARATUS

Filed June 8, 1927

Benjamin E. Miessner Inventor
By his Attorney

UNITED STATES PATENT OFFICE

BENJAMIN F. MIESSNER, OF SOUTH ORANGE, NEW JERSEY, ASSIGNOR, BY MESNE ASSIGNMENTS, TO RADIO CORPORATION OF AMERICA, OF NEW YORK, N. Y., A CORPORATION OF DELAWARE

ELECTRON DISCHARGE APPARATUS

Application filed June 8, 1927. Serial No. 197,314.

This invention relates to electron discharge devices and to a system employing such devices as repeaters or amplifiers. In particular the invention relates to 3-electrode vacuum tubes adapted for use in a system where in the filament of the tube is heated by alternating or other unsteady current flowing therethrough.

Heretofore the use of unsteady current in the filament has produced a number of effects which have contributed to a greater or less extent toward producing disturbing current variations in the plate circuit of the tube. Thus during momentary recurring periods of low current the temperature of the filament falls and the electron emission from the heated filament is momentarily reduced, which tends to decrease the flow of electrons to the plate electrode. Also the variations in the difference of potential between different portions of the filament tends to cause variations in the plate current. Portions of the filament which are momentarily at higher positive potential have the effect of diverting from the plate some of the electrons emitted from the lower potential portions of the filament, thus periodically robbing the plate of some of its supply of electrons.

The reduction or elimination of disturbing hum effects may be effected by the use of a filament of special design as is disclosed in my copending application, Serial No. 191,195, filed May 13, 1927, issued June 18, 1929 under Patent No. 1,718,059. In the present application I disclose a means additional to the filament for reducing or controlling the hum variations particularly those variations which are caused by the robbing effect above referred to.

In the particular form of my invention herein disclosed, my improved vacuum tube has a plate, filament and grid. The grid comprises a flat coil of wire surrounding the filament, which filament is of the V-type and extending between the legs of the V is a metal shield in the form of a strip or plate, which is secured at points along its edges to the turns of the grid coil. In this form of my invention the shield, because of its connection to the grid, is electrically part of the grid,

and when the grid is biased negatively the shield creates an electrostatic field of negative potential in the space between the legs of the filament. This field prevents electrons emitted from the negative leg of the filament from passing over to the positive leg and so reduces or eliminates the robbing effect.

Also the shield, which extends between the legs of the filament, acts as a mechanical barrier to the flow of electrons between the legs. Electrons which with the shield absent would pass directly from one leg to the other will, owing to the presence of the shield, be deflected toward the plate, and in this manner also the shield will serve to minimize the robbing effect.

While I illustrate my invention as applied to a vacuum tube having a filament of the V-type, I do not wish to limit the invention to use with a filament of any particular form. The invention in its broader aspects involves merely interposing a barrier to the flow of electrons from one portion of the filament through the evacuated space to another portion, or creating a field of force in the path which the electrons would normally follow in passing from one portion to another of the filament, which field has the effect of reducing the flow of electrons along such path.

Features and advantages of my invention other than those above noted will be apparent from the following description taken in connection with the accompanying drawings, which shows a vacuum tube and connected circuits, the tube being shown in perspective and a portion of the plate electrode of the tube being broken away to disclose the filament and grid structure.

Figure 1 illustrates my invention as applied to a V-type filament. Figure 2 illustrates the invention as applied to an M-type filament.

The tube 9 as shown encloses an evacuated space in which are located a filament 10, grid 11 and plate electrode 12. The filament 10 is of the V-type formed of lengths or legs 14 connected at their lower ends by nickel tubes 15 to leading-in wires 16, which wires are sealed through the glass neck of the tube. The legs are supported under tension by a

spring rod 20 and hook 18 of fine wire which engages the top bend of the filament.

The grid comprises a flat coil of wire 21, which surrounds the filament, the wire 21 being wound around spaced vertical rods 24. The lower ends of the rods 24 are sealed in the glass neck of the tube and one of the rods 24 connects with a wire 26 which forms the leading-in terminal of the grid.

10 The plate 12, which is spaced from and surrounds the grid 11, is formed of two thin sheet metal side members 28 bent toward one another and joined together near their side edges. The outer edges of the members 28 15 are pinched around supporting rods 29, which rods are sealed at their lower ends in the glass neck of the tube. A wire 30 connected with one of the rods 29 forms the leading-in terminal of the plate. The spring rod 20, which 20 supports the filament from the top, is in turn supported from the top of one of the rods 29 by an insulating glass member 32.

Positioned between the two legs 14 of the filament and extending at approximately 25 right angles to the plane of the filament is a thin metal strip or shield 35, which is welded at points along its side edges to the wire turns of the grid coil. This strip may be perforated or otherwise lightened in weight.

30 The circuit diagram of the drawings shows the filament heating circuit supplied from the secondary S of an alternating current transformer; the plate circuit energized from a source B of direct current, and a source of 35 potential C for supplying a negative biasing voltage to the grid 11. The plate and grid circuits are connected to the filament supply circuit through an adjustable tap T and a potentiometer resistance P connected across 40 the secondary S. The tube connected in the manner shown may be used as a radio frequency or audio frequency amplifier, or detector.

45 Due to the alternating heating current in the filament one leg of the filament is alternately of positive and negative potential with respect to the other leg. The strip 35 forms a shield between the legs of the filament and in the form of invention shown, this strip being connected to the grid coil, is maintained by the source C at a potential which is negative with respect to the negative leg of the plate. This shield operates in the manner above described to prevent electrons emitted 50 from the negative leg from passing to the positive leg and in this manner reduces the robbing effect.

55 When the filament is in the form of a W instead of a V three shields may be employed, one between each pair of lengths.

60 Figure 2 shows a filament 100 in the form of an M. The arm 20 has two hooks 18 to support the upper bends, and the hook 118, which is embedded in the press, supports the center lower bend of the M. Positioned between

each pair of legs of the filament 100 and supported by the grid coil 11 is a strip 35, as in Figure 1. In Figure 2 the anode and other elements have been omitted for the sake of clearness. It is apparent that instead of the 70 M-type of filament a W-type may be used.

In certain cases the shield 35 may be formed of non-conducting material such as glass, the glass shield functioning as a barrier between the different portions of the filament and so 75 reducing the flow of electrons between the portions. A tube with a non-conducting shield may be used when it is desired to operate a tube without negative grid bias, as is often the case with detector tubes.

80 In my patent hereinbefore referred to, I disclosed a vacuum tube designed for operation with alternating current in the filament and wherein provision is made for reduction of disturbing hum variations in the plate 85 circuit by the use of a filament of large diameter operated at low temperature and low voltage, or by the use in a single tube of two of such filaments connected in parallel. In the present invention, if desired, the filament 90 10 may be formed of relatively thin wire designed for operation at relatively high voltage. I may, however, secure the advantages gained of low voltage and low temperature operation by employing, as the filament 10, a 95 filament of large diameter and relatively low resistance. The diameter of the filament 10 may be made sufficiently large that its resistance is practically the same as the two parallel connected filaments disclosed in my co-pending application. When so made the filament 10 may be operated at approximately 100 the same low voltage which I employ for operation of the two filaments in parallel. The temperature of operation of the filament 10 at such low voltage will be low and this, together with the high heat storage capacity 105 of the large filament, will minimize the temperature variations of the filament and so 110 reduce the disturbing hum variations in the plate circuit.

115 For the sake of brevity and definiteness in setting forth the invention to be defined in the claims annexed hereto, I shall use the distinctive terms and definitions thereof as applied to my improved tube and set forth in my patent hereinbefore referred to, specifically in lines 113, page 5 to line 25, page 6 thereof.

120 In tubes using two spaced filaments connected in parallel there are four wires connected to the two filaments. These wires conduct away some of the heat generated in the filament by the heating current and therefore cool the ends of the two filaments. Since 125 there are four such connecting wires there are four paths through which heat may be lost from the filament, thus causing a portion at the end of each filament to lose its emitting power. In the form of filament disclosed in 130

the present application this heat loss is greatly reduced because only two lead wires are necessary instead of four. The supporting hook 18 which engages a bend at the top of the filament is of very thin wire and conducts a relatively small amount of the heat away from the filament.

5 I claim:—

- 10 1. In an electron discharge tube, a plate, a V-shaped filament, a grid comprising a coil of wire surrounding said filament, and a flat strip secured at points along its side to the turns of said coil, said strip extending laterally between the two legs of said filament.
- 15 2. In an electron discharge tube, a plate, a current-carrying V-shaped electron emissive filament, a grid surrounding said filament, and a flat metallic screen between the legs of said filament having its plane at right angles to the plane of said V-shaped filament and conductively connected to said grid.

20 In testimony whereof I hereunto affix my signature.

BENJAMIN F. MIESSNER.
